AWNNG FRAME

Henry S. Wilson and Henry Lauten,
New York, N. Y.

Application November 1, 1932. Serial No. 640,607

6 Claims. (Cl. 156—44)

This invention relates to new and useful improvements in awning frames.

The invention has for an object the construction of an awning frame which is characterized by a novel junction between an arm and support arm thereof adapted to be extended and to bend to a collapsed position in a simple and efficient manner.

As a further object of this invention it is particularly proposed to construct a novel junction to include a substantially U-shaped bend on one end of the arm and the outer arm of the U-shaped bend being formed with an out-turned free end, the bend and the said outer arm having a longitudinal slot, and to support said arm by the provision of a supporting screw engaging through the slot and mounted upon a support arm in a fashion so that said arm may be pivoted by sliding over the head of said screw.

Furthermore, with references to the previous paragraph it is also contemplated to so arrange the support arm with the out-turned free end of the outer arm of the U-shape to form an abutment to limit pivoting of the arm in one direction.

Still further it is proposed to arrange the novel junction in combination with a lazy tong structure and with certain links in a manner so as to obtain a folding awning frame thus equipped.

Furthermore, it is proposed to provide an arrangement where portions of said frame resiliently assume positions necessary in allowing the collapsed and extending of the awning frame.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a portion of a building having a window equipped with an awning constructed according to this invention.

Fig. 2 is a transverse elevational view of one of the sides of the awning frame.

Fig. 3 is a plan view of the awning frame per se.

Fig. 4 is a fragmentary view similar to a portion of Fig. 3 but showing a modified arrangement particularly of the joint between certain parts forming the frame.

Fig. 5 is a perspective view of another awning having a frame of different construction but in which the same purpose of the invention is embodied.

Fig. 6 is a view of the frame used in the awning shown in Fig. 5, but illustrated in a folded condition.

Fig. 7 is a fragmentary enlarged detailed view of one of the front corners of the awning illustrated in Fig. 5 shown in detail with the awning in section.

Fig. 8 is a front edge elevational view of Fig. 7.

Referring first to the form of the invention illustrated in Figs. 1-3 inclusive an awning 10 has been shown in an extended position over the window 11 of a building 12. The awning 10 is shown upon a suitable roller mounted upon the building by supports 13. The details of the supports for mounting of the awning upon the roller will not be given here since it forms no part of the invention.

The invention itself resides in the frame for supporting the front edge 14 of the awning 10. This frame has a transverse front support arm 15 adapted to be secured in any desirable manner upon the front edge 14 of the awning. At both ends the support arm 15 connects with collapsible arm structures which are identical to each other. Each of these arm structures comprises a collapsible lazy tongue structure having at one of its ends a pair of links 16 and 17 adapted for pivotal mounting upon a wall or other support for the awning.

The links 16 and 17 are shown pivotally connected upon brackets 18 secured upon the building 12. The collapsible lazy tong structure is formed at its other end with a projecting support arm 19. The arrangement is such that the lazy tong structure may be extended or retracted by pulling forward or pushing rearwards upon the projecting support arm 19. The links shown comprising the lazy tong structure, see Fig. 3 particularly, are shown double on certain lengths and used singularly on other lengths so as to form a firm supporting construction. The exact details of this particular lazy tong structure need not be gone into since it is immaterial how many links it is constructed of and as regards its details in the width. Similarly its length is also immaterial but it is necessary that it terminate at the front end in just one projecting support arm.

The details of the lazy tong structure comprises a link 20 pivotally connected at its ends respectively with the front end of the link 16 and

the rear end of the support arm 19. The link 17 pivotally connects at the point 21, which is intermediately of its ends, with an intermediate point upon the link 20. A link 22 pivotally connects with the front end of the link 17 and with an intermediate point 23 of the projecting support arm 19. The lazy tong structure may be collapsed, as clearly indicated in Fig. 2 by the dot and dash lines. It is limited in its extension by a screw 24 which threadedly engages in the link 20 so as to be adjustable as regards its extension, and the free end of this screw abuts against the side of the link 22. It will be noticed that while the screw 24 limits the extent to which the lazy tong structure can open it does not interfere with the closing of the lazy tong structure from its open position.

Each of the arms forming the frame of the awning includes an arm 24' having a lateral substantially U-shaped bend 25 at one end arranged so that the outer arm of the U-shaped bend terminates in an out-turned free end 26. The bend of the U-shaped bend and the outer arm is formed with a longitudinal slot 27, shown clearly in Figs. 7 and 8. A screw 28 engages through the longitudinal slot 27 and is supported upon the projecting arm 19. The arm 24' is so arranged that the out-turned free end 26 limits outward pivoting of the arm, with references to Fig. 3.

The arms 24' may pivot horizontally inwards as indicated by the dot and dash lines in Fig. 3 since the slots 27 may slide along beneath the heads of the screws 28. Upon the outer end of each of the arms 24' there is mounted a pivoted elbow comprising a socket member 29 hingedly connected with another socket member 30. The arm 24' threadedly engages in the socket member 29 allowing slight adjustments of the awning frame by reason of fully or partially engaging the threads. A link 31 threadedly engages in the socket 30 and at its free end is connected by a bracket 32 with the end of the support arm 15. A spring 33 is located between the sockets 29 and 30 and more particularly upon the pivots thereof and acts between these two sockets for normally urging them at a slight inclination towards each other. The full lines in Fig. 3 indicate the position in which the sockets 29 and 30 are normally urged by the spring 33.

The operation of the awning frame may be understood by first imagining the awning in its extended position, as shown in Fig. 1. In this position the awning frame is as shown in Figs. 2 and 3. Now then, when the awning is wound upon its roller it draws backwards on the support arm 15 which bends sockets 29 and 30 upon their pivots to the positions indicated by the dot and dash lines in Fig. 3. The joints of the arms 24' at 25 may bend by themselves as the joints 29 and 30 bend, but if they don't it is merely necessary to manually help them get started. When the awning has thus been partially collapsed, say about half way, the arms 24' will be fully pivoted inwards, and upon further winding up of the awning the lazy tong structure will be caused to collapse, until it assumes the position shown in Fig. 2. The awning now is completely in its collapsed position. Upon extending the awning, first the springs 33 extend the links 31 and the arms 24' and then the lazy tong structure extends until the awning is fully extended.

In Fig. 4 a modified form of the elbow upon each of the side arm structures in the awning frame is shown. More particularly this elbow

comprises sockets 29' and 30' pivotally connected by a rivet 33' and each of the sockets is provided with square shaped or other similar shaped openings 34 into which the ends of the arms 24' and links 31' engage. Set screws 35 threadedly engage the sockets 29' and 30' and are adapted to abut against the ends of the arm 24' and the link 31' so as to hold these parts in various extended positions which allow adjustments similar to the threads in the form shown in Fig. 3. This elbow is also provided with a spring 33 to cause the sockets 29' and 30' to assume the bent positions previously described.

In Figs. 5-8 inclusive another form of the invention has been disclosed which utilizes the principle of the arm with the U-shaped bend as previously described. To better understand this form of the invention an awning 40 has been illustrated supported at its rear end 40 and having its front end 42 attached upon the support arm 43. This support arm 43 extends the full width of the awning. The awning frame is concluded by an arm 44 on each of the sides of the awning 40 and the arm 44 is formed with a lateral substantially U-shaped bend 25 at one end and the outer arm of the U-shaped bend is formed with an out-turned free end 26. The bend of the U-shaped bend 25 and the outer arm of said U-shaped bend is formed with a longitudinal slot 27. A screw 28 engages through the slot 27 and through the support arm 43.

The rear ends of the arms 44 are adapted to be pivotally connected with brackets 45 for attachment upon the building or wall structure. The brackets 45 are so arranged as to allow the arms 44 to pivot in the vertical. When the awning frame is upon the awning, as shown in Fig. 5 in use it does not differ from any of the commercial frames now on the market. It is only when the awning is dismantled, that is, removed from the building, then the arms 44 may be pivoted to the collapsible position as shown in full lines in Fig. 6 or dot and dash lines in Fig. 7 to take up the smallest amount of compass and yet have its parts connected in a unit. The arms 44 may pivot to a closed position by reason of the slots 27 sliding over the heads of the screws 28. In the extended position the free out-turned ends 26 engage against the ends of the support arm 43 to limit outward pivoting.

It is to be understood that when the sidewalk is narrow, it is advisable to separate the awning frame and use only the lazy tong structure up to the bend 25 or the collapsible structure from bend 25 to the front support arm 15.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. In an awning frame, an arm having a lateral substantially U-shaped bend at one end with an out-turned free end on the outer arm of said U-shaped bend, the bend and the outer arm of said U-shape having a longitudinal slot, a support arm against the outer arm of said U-shaped bend, and a screw mounted upon said support arm engaging through said longitudinal slot for holding the arm movable from an extended position in which said out-turned free end prevents further

- motion to a position in which said arm is considered collapsed.
2. In an awning frame, an arm having a lateral substantially U-shaped bend at one end with an 5 out-turned free end on the outer arm of said U-shaped bend, the bend and the outer arm of said U-shape having a longitudinal slot, a support arm against the outer arm of said U-shaped bend, and a screw mounted upon said support 10 arm engaging through said longitudinal slot for holding the arm movable from an extended position in which said out-turned free end prevents further motion to a position in which said arm is considered collapsed, said U-shaped bend 15 being so arranged as to roll along over the head of the supporting screw in moving from the extended to the collapsed position.
3. In an awning frame, arms adapted for pivotal connection on their rear ends upon a 20 wall and at their front ends having laterally substantially U-shaped bends with out-turned free ends upon the outer arms of said bends, the bends and outer arms of said U-shaped bends having longitudinal slots, a support arm for attachment 25 upon the front end of an awning and engageable against the outer arms of said U-shaped bends, and screws mounted upon said support arms and engaging through said longitudinal slots for holding the arms movable from extended positions 30 in which said out-turned free ends engage against said support arm to positions in which said arms are substantially parallel with said support arm.
4. In an awning frame, arms adapted for pivotal connection on their rear ends upon a 35 wall and at their front ends having lateral substantially U-shaped bends with out-turned free ends upon the outer arms of said bends, the bends and outer arms of said U-shaped bends having longitudinal slots, a support arm for at- 40
- tachment upon the front end of an awning and engageable against the outer arms of said U-shaped bends, and means projecting from the support arms and engaging through said longitudinal slots for holding the arms movable from 80 extended positions in which said out-turned free ends engage against said support arm to positions in which said arms are substantially parallel with said support arms.
5. In an awning frame, arms adapted for pivotal connection on their rear ends upon a wall and at their front ends having lateral substantially U-shaped bends with out-turned free ends upon the outer arms of said bends, a support arm for attachment upon the front end of an awning and engageable against the outer arms of said U-shaped bends, and means mounted upon the support arms and engaging the U-shaped bends for holding the arms movable from extended 90 positions in which said out-turned free ends engage against said support arm to positions in which said arms are substantially parallel with said support arm.
6. In an awning frame, arms adapted for pivotal connection on their rear ends upon a wall and at their front ends having lateral substantially U-shaped bends, the bends and outer arms of said U-shaped bends having longitudinal slots, a support arm for attachment upon the front end of an awning and engageable against 100 the outer arms of said U-shaped bends, screws mounted upon said support arms and engaging through said longitudinal slots for holding the arms movable from extended positions to positions in which said arms are substantially parallel 105 with said support arm, and means for limiting the outward movement of the arms.
